(57) **CLAIM**

We claim the ornamental design for a panel board for electroluminescence module, as shown and described.

DESCRIPTION

FIG. 1 is a top perspective view of a first embodiment of a panel board for electroluminescence module of the present invention;

FIG. 2 is a front view thereof;

FIG. 3 is a rear view thereof;

FIG. 4 is a first side view thereof, the second side being a mirror image;

FIG. 5 is a top view thereof, the bottom view being a mirror image;

FIG. 6 is a top perspective view of a second embodiment of a panel board for electroluminescence module of the present invention;

FIG. 7 is a front view thereof;

FIG. 8 is a rear view thereof;

FIG. 9 is a first side view thereof, the second side being a mirror image;

FIG. 10 is a top view thereof, the bottom view being a mirror image;

FIG. 11 is a top perspective view of a third embodiment of a panel board for electroluminescence module of the present invention;

FIG. 12 is a front view thereof;

FIG. 13 is a rear view thereof;

FIG. 14 is a first side view thereof, the second side being a mirror image; and,

FIG. 15 is a top view thereof, the bottom view being a mirror image.
